UNITED STATES PATENT OFFICE

ORSON W. BRENZER, OF PHILADELPHIA, PENNSYLVANIA

WIRESPLICING DEVICE

Application filed May 6, 1932. Serial No. 609,534.

This invention relates to improvements in wire splicing or twisting devices particularly adapted for use in forming splices between meeting wires in connecting the ends of telephone and other cable sections carrying a multiplicity of wires.

An object of the invention is to provide a twisting device of novel and advantageous construction wherein the mechanism thereof is carried and operated by two pivotally connected handles, normally spaced from each other and capable of being operated like the handles of an ordinary pair of pliers, and wherein the operation of the twisting mechanism is effected by the movement of the handles toward each other. Another object is to provide means for the engagement of the wires to be twisted at three spaced places and for the close twisting of the wires between two of said places and for the more open twisting of the wires between two of said places. Another object is to provide means for cutting the wires after the twisting thereof. Another object is to provide means for the discharge of the discarded cut off ends of the wires following the twisting and cutting thereof.

With the foregoing and related objects in view, the invention consists of the elements and the combinations of them hereinafter described and claimed.

In the accompanying drawings, illustrating the invention,

Figure 1 is a front view of a wire twisting device showing one form of embodiment of the invention.

Figure 2 is a side view thereof.

Figure 3 is a top view thereof.

Figure 4 is a section through the wire twisting mechanism, on line 4-4 of Fig. 1.

Figure 5 is a section through the wire twisting mechanism, on line 5-5 of Fig. 4, showing the end portions of two wires to be spliced therein and showing one of the wire clamps in the closed position clamping the wires.

Figure 6 is a transverse section through the wire twisting mechanism on line 6-6 of Fig. 5.

Figure 7 is a sectional detail showing a

part of the mechanism for operating one of the wire clamps.

Figure 8 is a view of the two wires shown in Fig. 5 showing the condition thereof after the same have been twisted by the device and the discarded portions thereof cut and removed therefrom.

Referring to the drawings, 2 and 3 designate two handles which are pivotally connected at 7. The handle 2 is provided with a supporting arm 8 which projects fixedly therefrom, and the handle 3 is provided with an operating arm 9 which projects fixedly therefrom. The handles 2 and 3 are held normally in the separated or open position, shown in the drawings, by a suitable spring 10, interposed between and connected to them, and the parts are constructed and related so that the handles may be grasped in one hand and, by the pressure thereof, moved toward each other against the resilient action of the spring to move the arms 2 and 3 toward each other, similar to the action of a pair of pliers; and, after the handles have been thus moved toward each other and the pressure of the hand causing such movement has been removed, the spring 10 will return the handles 2 and 3 and the arms 8 and 9 to the open or normal position in the hand of the user, for a succeeding closing operation.

Projecting from the supporting arm 8 and rigidly secured thereto by means of a screw 11 is a cylindrical member 12 which forms, in effect, an integral part of the arm 8. The member 12 has a central, longitudinally extending bushing 13 suitably secured therein. The bushing 13 extends from the inner end of the member 12 to a point near the outer end thereof and the central bore or passage 14 provided by the bushing is made flaring at its outer end and joins and forms a continuation of a flaring opening in the outer end portion of the member 12, as shown in the drawings, to permit wires easily to be inserted into and projected through the bushing from the outer end of the member 12.

The inner end portion of the member 12 has an axial bore or opening formed therein which houses a bevel gear wheel 15 which is rotatably mounted on the inner end por-

80

tion of the bushing 13. The hub of the gear wheel 15 has an annular groove 16 therein which receives a projection on the inner end of the screw 11 to prevent longitudinal displacement of the gear wheel on the bushing 13.

The gear wheel 15 coacts with a bevel gear wheel 17 fixed on a shaft 18. One end portion of the shaft 18 turns in a bearing on the supporting arm 8 and the other end portion of the shaft 18 turns in a bearing formed in one side of the bushing 13. Fixed on the shaft 18 is a pinion 19 which is in mesh with a toothed segment 20. One end of the segment 20 is embraced by the bifurcated end of the operating arm 8 and connected thereto by means of a screw 21 which extends through the arm 8 and through a slot 22 in the segment. The curvature of the segment 20 is concentric with the pivot of the handles 2 and 3, and the segment extends between and is held in place by the pinion 19 and a part 23 of the supporting arm 8. The operating arm 9 has a leaf spring 24 secured thereto by means of a screw 25, and the free end portion of the spring 24 bears against the adjacent end of the segment 20 and maintains one end wall of its slot 22 normally in contact with the screw 21, as shown in Fig. 1, to provide a yielding connection between the segment and the arm 8 for a purpose hereinafter explained. When the handles 2 and 3 are moved toward each other, the segment 20 is projected through the space between the pinion 19 and part 23 and rotates the pinion and bevel gear wheels 15 and 17, and the extent of the projection of the segment is limited by a shoulder 26 thereon engaging the part 23 of the supporting arm 8.

The bevel gear wheel 15 is adapted to rotate a wire twisting device 27 which is arranged in axial alignment with and inwardly of the cylindrical member 12. The wire twisting device 27 has a centrally arranged, telescopic, hollow shaft 28 formed by upper and lower telescopic sections 29 and 30, respectively. The upper end of the upper section 29 is spaced from the flush ends of the member 12 and hub of bevel gear wheel 15 and end of bushing 13, and the section 29 is connected to the hub of the gear wheel 15 by an arm 31, which is arranged at one side of the section 29 and the hub of the gear wheel 15, as clearly shown in Figs. 4, 5 and 6.

The lower portion of the lower shaft section 30 extends through and is slidably fitted within a bushing 32 which is rotatably mounted in a carrying arm 33 therefor. The upper end of the section 30 has a head or member 34 formed thereon and the lower end of the section 30 has a collar 35 secured thereon below the bushing 32. Encircling the section 30 between the head 34 and a washer on the bushing 32 is a helical spring 36 which urges the section 30 upwardly through the

bushing. Normally the collar 35 engages the bottom of the bushing 32 and limits the upward movement of the section 30 therethrough, as shown in Fig. 4.

The top of the bushing 32 has an annular flange 37 formed thereon which extends over the arm 33, and the opposing surfaces of the flange 37 and arm 33 have oppositely disposed annular grooves formed therein to provide a raceway for an annular series of balls to provide an antifriction thrust bearing between the bushing 32 and the arm 33.

Surrounding the upper telescopic shaft section 29 beneath a head 38 thereon is a slideable collar 39 having lugs 40 extending outwardly from opposite sides thereof, and fulcrumed in these lugs, at 41, are two oppositely disposed clamp levers 42. The upper ends of these levers have clamping arms 43 formed thereon which extend inwardly over the upper end of the upper shaft section 29 in close proximity thereto, and the lower ends of the levers 42 have arms 44 formed thereon, as clearly shown in Figs. 1 and 5.

One side of the clamp arms 43 are adapted to contact with a flat surface of the arm 31 connecting the shaft section 29 and bevel gear wheel 15 to cause the levers 42 and the collar 39 to rotate with the section 29, and one side of the levers 42 are in close proximity to and adapted to contact with a transversely extending wall 45 formed on the head 34 to cause the lower shaft section 30 to rotate with the upper section 29.

The upper end of the head 34 is provided with downwardly and outwardly inclined cam surfaces 46 and with additional downwardly and outwardly inclined cam surfaces 47 extending from the lower ends of the surfaces 46 at steeper inclines relatively thereto. These surfaces are adapted to engage the inner ends of the lever arms 44 for a purpose hereinafter explained. The wall 45 is provided with lugs 48 which project over the lever arms 44 and which are adapted to engage the same for a purpose hereinafter described.

The carrying arm 33 for the bushing 32, at the lower end of the wire twisting device, projects fixedly from the lower end of a shaft 49 which is arranged laterally of and parallel to the telescopic shaft 28. This shaft 49 is slidable longitudinally in a bearing 50 formed on the supporting arm 8 and having bifurcated head 51 formed on or secured to the upper end thereof and embracing the segment 20. The supporting arm 8 is provided with a projection or bracket 52 on which a lever 53 is fulcrumed, at 54. The lever 53 is provided with an arm 55 having a rounded free end which rests normally in a socket 56 formed in the bottom of the free end portion of the segment 20, and it is also provided with an arm 57 which extends into the bifurcated head 51 between the base portion thereof and

a transverse pin 58 connecting the sides of the head 51.

The lever 53 is so related to the segment 20 that when the handles 2 and 3 are moved 5 toward each other the segment 20 will be projected over the lever arm 55 and move it out of the socket 56 and thereby rock it on its fulcrum 54 from the position shown by full lines in Fig. 7, to the position shown by dot-and-dash lines therein, and the bottom of the segment 20 will prevent the return of the lever 53 to the full line position until the handles 2 and 3 and segment 20 are returned 10 to the normal position. When the handles 15 and segment are returned to normal position, a projection 59 on the free end of the segment 20 engages the lever arm 55 and moves it back into the socket 56 and thereby returns the lever 53 to the normal position. The lever 20 53 is thus operated by the segment 20 for the purpose of operating the wire clamping levers 42 of the wire twisting device 27, as will be hereinafter described.

The cylindrical member 12 carries a wire 25 clamping lever 60 which is located within a slot which extends through one side of the member 12 and through one side of the bushing 13. The lever 60 is fulcrumed at 61 on the bushing 13, and it has an arm 62 which 30 is adapted to enter the bore 14 of the bushing 13 and clamp wires therein between the free end of the lever arm 62 and the opposing wall of the bushing bore. The lever 60 has another arm 63 which extends outwardly 35 from the member 12 and has its free end pivotally connected to a head 64 on the lower end of a pin 65 whose upper end portion is slidably in a bracket 66 which projects fixedly from the member 12. Encircling the pin 40 65 between the head 64 thereon and the bracket 66 is a helical spring 67 which urges the lever arm 62 into wire clamping position within the bushing bore 14 and which urges the lever arm 63 into contact with the 45 upper or opposing surface of a segmental cam plate 68 which controls the movements of the lever 60. One end of the cam plate 68 is pivoted, at 69, to a bracket 70 which is formed on the operating arm 9, and the other 50 end portion of the cam plate 68 is slidably connected to the member 12 by a plate or block 71 which is secured within the slot in the member 12 and which projects therefrom through a long slot 72 in the cam plate 68 55 and has a retaining head 73 on the outer end thereof between which and the member 12 the cam plate 68 is adapted to move. The curvature of the slot 72 in the cam plate 68 is concentric with the pivot of the handles 2 and 3, and the upper or lever arm opposing 60 surface of the cam plate 68 is provided with two spaced raised portions 74 and 75 and an interposed depressed portion 76 and with suitable inclined portions connecting them, 65 as shown in Fig. 1; and when the handles 2

and 3 are moved toward each other, said portions will control the movements of the wire clamping lever 60, as will be presently described.

The operating arm 9 carries a wire cutting 70 knife 77 which is secured to the bracket 70 thereon and which is provided with an arm 78 which projects toward the inner end of the cylindrical member 12. The free end of the knife arm 78 has an inclined cutting edge 79 positioned to sweep across the inner end of the bushing 13 and the inner end of the bore 14 therein in close proximity thereto and sever wires extending through the bushing 13 and telescopic shaft 28 during the 80 final movement of the handles 2 and 3 when they are moved toward each other for the operation of the device.

The handles 2 and 3 are constructed to be 85 grasped in one hand of a workman and forced toward each other from the normal position shown in Fig. 1, against the action of the spring 10 to cause the segment 20, the cam plate 68 and the knife 77 carried by the operating arm 9 to sweep through and across the mechanism and parts carried by the supporting arm 8; and, thereafter, the pressure on the handles is released and the spring 10 returns them and the parts carried thereby to the normal or open position; and one 90 complete cycle of operations of the mechanism of the device takes place during this in and out movement of the handles 2 and 3.

The operation of the device is as follows:

The end portions of two wires 80 (Fig. 5) 100 to be spliced are brought together and a preliminary twist 81 of one or two turns is given to them by hand and the free end portions of the wires extending from the twist 81 are inserted into the outer end of the member 12 105 and bushing 13 and projected through the same and through the hollow telescopic shaft 28 by hand until the portions of the wires which extend laterally from the twist 81 to the spaced ends of the cable sections carrying them engage the outer end of the member 12, as shown in Fig. 5. When the wires 80 are thus inserted, the clamping levers 42 110 are in the open position shown in Fig. 1, and the wires 80 are held in a taut condition, or substantially so, between the preliminary twist 81 therein and the ends of the cable sections from which the wires project.

The wires 80 having been thus inserted into the device, the workman, holding the handles 2 and 3 in the grasp of one hand, forces the handles toward each other while a finger of the other hand holds the wires against the outer end of the member 12 during the initial movement of the handles toward each other. During the initial movement of the handles toward each other, the segment 20 moves the lever 53 from the full line position shown in Fig. 7 to the dot-and-dash line position shown therein, and this 125 130

operation causes the lever arm 57 to engage the pin 58 and slide the shaft 49 upwardly or outwardly and cause the arm 33 and bushing 32 to move toward the cylindrical member 12. As the bushing 32 moves toward the member 12, it causes the spring 36 to move the head 34 and lower telescopic shaft section 30 toward the member 12. The first movement of the head 34 causes the levers 42 to raise the collar 39 into engagement with the head 38 on the upper telescopic shaft section 29, and, thereafter, the upward movement of the collar 39 ceases, and the continued movement of the head 34 causes its inclined surfaces 46 and 47 to force the lower ends of the levers 42 apart and the upper ends thereof toward each other until the clamping arms 43 engage and firmly clamp the wires 80 between them, as shown in Figs. 5 and 6.

20 After the wires 80 have been thus clamped by the arms 43, further upward movement of the head 34 is prevented thereby, and, thereafter, as the lever 53 completes its movement to the dot-and-dash line position, the bushing 32 moves away from the collar 35 on the lower end of the lower shaft section 30 and compresses the spring 36 and causes the clamp arms 42 to firmly clamp the wires 80 with a yieldable pressure which will compensate for variations in the wires and permit wires of varying diameters to be clamped and firmly held without any adjustment of parts of the device. After the clamping arms 43 have engaged the wires 80, the workman may remove his finger from its position holding the wires in contact with the outer end of the member 12.

40 About the time that the clamping arms 43 are moved into clamping position, or immediately thereafter, the high portion 74 of the cam plate 68 moves from beneath or out of contact with the lever arm 63 and permits the spring 67 to operate the lever 60 to move the arm 62 thereof into the bore of the bushing 13 and clamp the wires 80 therein at a point spaced from the clamping arms 43.

50 The toothed segment 20 starts to rotate the wire twisting device 27 immediately after the handles 2 and 3 start their movement toward each other and it continues to rotate the device 27 and cause it to twist the wires together between clamping arm 62 of the lever 60 and the clamping arms 43 of the levers 42 until the portions of the wires extending 55 between the two clamps have been closely twisted together in the condition shown below the line 82 in Fig. 8. This done, the high portion 75 of the cam plate 68 engages the arm 63 of the clamping lever 60 and 60 moves the clamping arm 62 thereof out from within the bore of the bushing 13 and causes it to release the wires 80 therein; and, thereafter, the continued rotation of the twisting device, under the influence of the continued 65 movement of the handles 2 and 3 toward

each other, causes the twisting device 27 to produce the more open twists in the wires 80 between the parts thereof previously engaged by the clamping end of the lever arm 62 and the preliminary twists 81 in the wires 80, as illustrated at 83 above the line 82 in Fig. 8.

70 After the open twists 83 have been produced in the wires 80, the twisting device comes to rest with the arm 31 connecting it with the bevel gear wheel 15 out of the path of movement of the projecting arm 78 of the wire cutting knife 77 and the further rotation of the device 27 is prevented by the engagement of the shoulder 26 of the segment 20 with the part 23 of the supporting arm 8; while the spring 24, engaging the end of the segment 20, yields and permits the final movement of the handles 2 and 3 toward each other.

75 On or about the time the twisting device 27 ceases to rotate, the cutting edge 79 of the knife arm 78 moves across the inner end of the bore 14 in the bushing 13 in close proximity to the inner end of the bushing and engages and severs the twisted wires substantially in the plane of the inner end of the bushing, as the final movement of the handles 2 and 3 toward each other takes place.

80 After the twisted wires have been severed, as just described, the workman permits the spring 10 to return the handles 2 and 3 to the normal, open position shown in Fig. 1, and the return of the handles to the normal position effects the return of the several parts of the mechanism of the device to the normal position; and, when the lever 53 is returned to the full line position, shown in Fig. 7, in thus being returned to normal position, it lowers the shaft 30 and arm 49 until the bushing 32 engages the collar 35 and prevents further relative movement between the arm 33 and lower shaft section 30, and, thereafter, during the final downward movement of the arm 33, the head 34 on the shaft section 30 is moved downwardly causing its lugs 48 to engage the arms 44 of the levers 42 and move the lower ends of the levers toward each other for the separation of their clamping arms 43 to the open position shown in Fig. 1, thereby completing the return of all the parts to the normal position for a succeeding wire twisting operation.

85 When the levers 42 are restored to the normal position, the separation of the clamping arms 43 thereof releases the cut-off end portions of wires previously clamped thereby and such cut-off end portions are discharged by gravity from their position within the telescopic shaft 28.

90 At any time after the knife has cut the wires 80 at the inner end of the bushing 13, the entire device may be withdrawn from the twisted wires within the bushing, leav-

ing them connected with twisted portions as shown in Fig. 8.

It will be understood that the outer end portions of the member 12 and bushing 13 therein constitute one means for receiving and holding the wires to be twisted, that the clamping arms 42 constitute another means for receiving and holding the said wires, and that the lever arm 62 and the opposing wall 10 of the bushing 13 constitute a third means for receiving and holding the said wires, and that the said third means is located between and spaced from the two means first mentioned, for the production of the long or open 15 wire twists between the first and third named means, and for the production of the short or compact wire twists between the second and third named means.

I claim:

20 1. The combination of a support, means thereon for receiving and holding a pair of wires, a rotatable twisting device, a wire clamp carried by the twisting device and movable thereon into closed and open positions, means to rotate said device, and means to operate said clamp.

25 2. The combination of a support, means thereon for receiving and holding a pair of wires, a rotatable twisting device, a wire clamp carried by the twisting device and movable thereon into closed and open positions, means to rotate said device, means to operate said clamp, and means for cutting the wires between the first named means and the clamp.

30 3. The combination of a support, means thereon for receiving and holding a pair of wires, a rotatable twisting device, a wire clamp carried by the twisting device and movable thereon into closed and open positions, a second wire clamp carried by the support and located between and spaced from said means and the first named clamp, means to close said clamps, means to open the first 35 named clamp, and means to open said second clamp after the opening of the first named clamp.

40 4. The combination of a support, means thereon for receiving and holding a pair of wires, a rotatable twisting device, a wire clamp carried by the twisting device and movable thereon into closed and open positions, a second wire clamp carried by the support and located between and spaced from 45 said means and the first named clamp, means to close said clamps, means to open the first named clamp, means to open said second clamp after the opening of the first named clamp, and means for cutting the wires between said clamps.

45 5. The combination of a support, a rotatable twisting device, a wire clamp carried by the twisting device and movable thereon into closed and open positions, a second wire clamp carried by the support in spaced rela-

tion to the first named clamp, means to rotate said device, and means to close and open said clamps.

6. The combination of a support, a rotatable twisting device, a wire clamp carried by the twisting device and movable thereon into closed and open positions, a second wire clamp carried by the support in spaced relation to the first named clamp, means to rotate said device, means to close and open said clamps, and means for cutting the wires between said clamps.

7. The combination of a support, means thereon for receiving and holding a pair of wires, a hollow shaft adapted to receive said wires, a rotatable twisting device associated with said shaft, means to rotate said device, a wire clamp carried by the twisting device and movable thereon into closed and open positions, and means to close and open the clamp.

8. The combination of a support, means thereon for receiving and holding a pair of wires, a hollow shaft adapted to receive said wires, a rotatable twisting device associated with said shaft, means to rotate said device, a wire clamp carried by the twisting device and movable thereon into closed and open positions, means to close and open the clamp, and means for cutting the wires between the first named means and said clamp.

9. The combination of a support, means thereon for receiving and holding a pair of wires, a hollow rotatable twisting device having an axial opening extending through the same to receive said wires, means to rotate said device, a wire clamp carried by the twisting device and movable thereon into closed and open positions, and means to close and open the clamp.

10. The combination of a support, means thereon for receiving and holding a pair of wires, a hollow rotatable shaft adapted to receive said wires, a wire clamp carried by the shaft and movable thereon into closed and open positions, a member movable longitudinally of the shaft, means for moving said member, means operated by said member when moved in one direction to close the clamp, and means operated by said member when moved in the reverse direction to open the clamp.

11. The combination of a support, means thereon for receiving and holding a pair of wires, a hollow rotatable shaft adapted to receive said wires, a wire clamp carried by the shaft and movable thereon into closed and open positions, a member movable longitudinally of the shaft, yieldable means for moving said member, means operated by said member when moved in one direction to close the clamp, and means operated by said member when moved in the reverse direction to open the clamp.

12. The combination of a support, means

thereon for receiving and holding a pair of wires, a hollow rotatable shaft adapted to receive said wires, a wire clamp carried by the shaft and movable thereon into closed and 5 open positions, a member movable longitudinally of the shaft, an operating arm for said member, means for moving said arm, a yieldable operating connection between said arm and said member, means operated by said 10 member when moved in one direction to close the clamp, and means operated by said member when moved in the reverse direction to open the clamp.

13. The combination of a support, means 15 thereon for receiving and holding a pair of wires, a rotatable twisting device provided with a wire clamp having a pivotally mounted arm movable into clamping and releasing positions, a reciprocable member, means to 20 reciprocate said member, means operated by said member when moved in one direction to move said arm into clamping position, and means operated by said member when moved in the reverse direction to move said arm into 25 releasing position.

14. The combination of a support, means thereon for receiving and holding a pair of wires, a rotatable twisting device provided with a clamp having a pair of oppositely 30 disposed pivotally mounted arms adapted to receive said wires between them and movable into clamping and releasing positions, a reciprocable member, means to reciprocate said member, means operated by said member 35 when moved in one direction to move said arms into clamping position, and means operated by said member when moved in the reverse direction to move said arms into releasing position.

40 15. The combination of a support, means thereon for receiving and holding a pair of wires, a rotatable twisting device, means on said device for engaging said wires and causing them to rotate therewith, a part movable 45 on the support into and out of an operative position engaging said wires and preventing the twisting thereof between and in spaced relation to the first named means and said device, means to rotate said device, and means 50 to move said part into and out of said operative position.

16. The combination of a support, means thereon for receiving and holding a pair of wires, a rotatable twisting device, means on 55 said device for engaging said wires and causing them to rotate therewith, a part movable on the support into and out of an operative position engaging said wires and preventing the twisting thereof between and in spaced 60 relation to the first named means and said device, means to rotate said device, means to move said part into and out of said operative position, and means for cutting said wires between said part and said device.

65 17. The combination of a support, means

thereon for receiving and holding a pair of wires, a rotatable twisting device, means on said device for engaging said wires and causing them to rotate therewith, an arm pivotally mounted on the support and movable into and out of an operative position engaging said wires and preventing the twisting thereof between and in spaced relation to the first named means and said device, means to rotate said device, a cam for moving said arm, and means for moving said cam.

18. The combination of a support, means thereon for receiving and holding a pair of wires, a rotatable twisting device, means on said device for engaging said wires and causing them to rotate therewith, an arm pivotally mounted on the support and movable into and out of an operative position engaging said wires and preventing the twisting thereof between and in spaced relation to the first named means and said device, means to rotate said device, a spring urging said arm toward its operative position, a cam for moving said arm from its operative position, and means for moving said cam.

19. The combination of a pair of pivotally connected handles movable toward each other from a normal position spaced from each other, one of said handles having a supporting arm extending therefrom and the other of said handles having an operating arm extending therefrom, means on the supporting arm for receiving and holding a pair of wires, a rotatable twisting device carried by the supporting arm and provided with means to receive said wires and cause them to rotate therewith, and means operated by said operating arm for rotating said device.

20. The combination of a pair of pivotally connected handles movable toward each other from a normal position spaced from each other, one of said handles having a supporting arm extending therefrom and the other of said handles having an operating arm extending therefrom, means on the supporting arm for receiving and holding a pair of wires, a rotatable twisting device carried by the supporting arm and provided with means to receive said wires and cause them to rotate therewith, a gear rack operated by said operating arm, and gearing carried by the supporting arm and operatively connected to said rack and to said device to rotate the latter.

21. The combination of a pair of pivotally connected handles movable toward each other from a normal position spaced from each other, one of said handles having a supporting arm extending therefrom and the other of said handles having an operating arm extending therefrom, means on the supporting arm for receiving and holding a pair of wires, a rotatable twisting device, a wire clamp carried by the twisting device and movable thereon into closed and open posi-

tions, means operated by said operating arm for rotating said device, and means operated by said operating arm to operate said clamp.

22. The combination of a pair of pivotally connected handles movable toward each other from a normal position spaced from each other, one of said handles having a supporting arm extending therefrom and the other of said handles having an operating arm extending therefrom, means on the supporting arm for receiving and holding a pair of wires, a rotatable twisting device carried by the supporting arm and provided with means to receive said wires and cause them to rotate therewith, a part carried by the supporting arm and movable into and out of an operative position engaging said wires and preventing the twisting thereof between and in spaced relation to the first named means and said device, means operated by said operating arm for rotating said device, means operated by said operating arm to move said part into and out of said operative position, and a knife carried by said operating arm and operated thereby to cut said wires.

23. The combination of a pair of pivotally connected handles movable toward each other from a normal position spaced from each other, one of said handles having a supporting arm extending therefrom and the other of said handles having an operating arm extending therefrom, means on the supporting arm for receiving and holding a pair of wires, a rotatable twisting device carried by the supporting arm and provided with means to receive said wires and cause them to rotate therewith, means operated by said operating arm for rotating said device, and a knife carried by said operating arm and operated thereby to cut said wires.

24. The combination of a pair of pivotally connected handles movable toward each other from a normal position spaced from each other, one of said handles having a supporting arm extending therefrom and the other of said handles having an operating arm extending therefrom, means on the supporting arm for receiving and holding a pair of wires, a rotatable twisting device, a wire clamp carried by the twisting device and movable thereon into closed and open positions, means operated by said operating arm for rotating said device, means operated by said operating arm to operate said clamp, and a knife carried by said operating arm and operated thereby to cut said wires.

25. The combination of a pair of pivotally connected handles movable toward each other from a normal position spaced from each other, one of said handles having a supporting arm extending therefrom and the other of said handles having an operating arm extending therefrom, means on the supporting arm for receiving and holding a pair of wires, a rotatable twisting device carried by the supporting arm and provided with means to receive said wires and cause them to rotate

therewith, a part carried by the supporting arm and movable into and out of an operative position engaging said wires and preventing the twisting thereof between and in spaced relation to the first named means and said device, means operated by said operating arm for rotating said device, means operated by said operating arm to move said part into and out of said operative position, and a knife carried by said operating arm and operated thereby to cut said wires.

In testimony whereof, I affix my signature.
ORSON W. BRENIZER.
